UNITED STATES PATENT OFFICE.

WILLIAM S. WITTEN, OF CHICAGO, ILLINOIS.

LATCH.

Application filed April 5, 1920. Serial No. 371,186.

To all whom it may concern:

Be it known that I, WILLIAM S. WITTEN, a citizen of the United States, and a resident of Chicago, in the county of Cook and State of Illinois, have invented certain new and useful Improvements in Latches, of which the following is a specification, reference being had to the accompanying drawings.

My invention relates to latches of the type comprising a latching member in the form of a heavy bolt suspended in horizontal position at the lower end of a pendulous bar, and the principal object of my invention is to provide a new and improved form and arrangement of means for mounting the latching member in position, for protecting it from the weather, and for locking it in operative latching position, the arrangement being such that the latch is adapted for use with either right-hand or left-hand doors. The preferred means by which I have accomplished my object is illustrated in the drawings and is hereinafter specifically described. That which I believe to be new and desire to cover by Letters Patent is set forth in the claims.

In the drawings,—

Fig. 1 is a face view of my improved latch in position upon a gate, a small portion only of which is shown;

Fig. 2 is an enlarged detailed view, being partly a section taken on line 2—2 of Fig. 1 and being partly broken away; and

Fig. 3 is an enlarged front view of my improved latch removed from the gate and with the face plate also removed, a changed position of the latch member being shown in dotted lines.

Referring to the drawings, 10 indicates a gate upon which is mounted a casing 11 as shown in Fig. 2, the complete casing comprising a cover plate or face plate 12. The latching mechanism carried by the casing 11 as hereinafter described is adapted to engage a keeper 13 mounted in suitable position upon a post 14.

The latching member comprises a heavy latching-bolt 15 carried at the lower end of a pendulous bar 16, in the construction shown the bolt 15 being formed integral with the bar 16. The bar 16 is suspended from a rock-shaft 17, which is pivotally mounted by means of bushings 18 fitted in suitable sockets in the opposite faces of the casing. The inner end of the shaft 17 is made square in cross section and fits in a

square hole in the upper end of the bar 16, as shown in Fig. 3, and the outer end portion 19 of said shaft is bent at right angles. By this construction the shaft serves not only to pivotally support the latch member, but also as a convenient handle for moving it out of operative position. As indicated by dotted lines in Fig. 3, measuring from the bar 16 the inner end portion of the bolt 15 is longer and, therefore, heavier than its outer end portion; consequently, gravity causes it to stand normally in its operative position, but it may be swung back out of operative position, as indicated by the dotted lines, either by means of the handle 19, or by its engagement with a beveled keeper plate 21 in the act of closing the gate. As it is desirable that the bolt return instantly to its operative position after passing the keeper plate so that it will be sure to catch when slammed. I have provided a set-screw 22 mounted in the wall of the casing in position to be struck by the pendulous bar 16 when it has swung inward far enough to carry the bolt 15 out of engagement with the keeper. The result is that when the bolt is thrown inward quickly, as by the slamming of the gate, the bar 16 strikes the set screw forcibly and is caused to rebound and carry the bolt into operative position more quickly than would otherwise be the case. As the bolt 15 is of considerable length and lies close to the side walls of the casing, it is supported against twisting strains by the walls of the casing, and, therefore, the bar 16 may be made comparatively light, as its principal function is to sustain and guide the bolt 15 in its movement rather than to resist the lateral strains to which it is subjected in holding the gate against swinging.

For locking the bolt 15 in operative position, a special form of lock is provided which is constructed and arranged so that the latch as a whole may be used for either right-hand or left-hand doors or gates. In order to meet this requirement, keyholes are provided in both faces of the latch casing to be used alternatively, depending upon which face of the casing is outermost. The locking mechanism for the latch comprises a casing 23 reversibly mounted in a suitable pocket formed in the latch casing below the latching-bolt 15 and provided with a locking-bolt 24 located centrally with respect to the lock-casing 23 so that reversal of the lock-casing does not change the relation of the

locking bolt 24 to the latch bolt 15. For holding the lock-casing 23 in position in the latch casing, it is provided with a lug 25 which projects from one face thereof and is 5 adapted to engage one of the key holes 26 in the opposite latch casing. The face of the lock-casing 23 is provided with a key hole 27 adapted to register with the key hole 26 in the adjacent face of the latch casing.

10 As will be appreciated, the bolt 15 in moving out of operative position swings inward and upward about the rock shaft 17 as a center, and in order to make the locking mechanism as effective as possible it is so 15 arranged that the locking bolt 24 has an extended engagement with the latch bolt with the bearing faces of said members in a plane substantially normal to the line of thrust of the latch bolt against the locking bolt.

20 This result is effected in the construction shown by arranging the locking mechanism so that when the locking bolt is projected it occupies a diagonal position with respect to the latching bolt when the latter is in its 25 operative or latching position. This also provides a bearing for the locking bolt against its casing which lies above the lower portion of the latching-bolt 15 so that said casing helps to sustain the locking bolt 30 against extraordinary strains.

What I claim as my invention and desire to secure by Letters Patent, is--

1. A latch comprising a casing, a latch-bolt movably mounted in said casing, and a 35 unitary lock reversibly mounted in said casing and having a locking-bolt adapted in either position of the lock to engage said latch bolt and hold it in operative position.
2. A latch comprising a casing having 40 keyholes in opposite sides thereof, a latch-bolt movably mounted in said casing, a unitary lock reversibly mounted in said casing, said lock having a keyhole adapted to register with the keyholes in said casing, a locking-bolt adapted in either position of 45 said lock to engage said latch-bolt for holding it in operative position, and a lug at one side of said lock adapted to fit in one or the other of said keyholes.
3. A latch comprising a casing, a latching-bolt movably mounted in said casing, a lock-casing removably mounted in a pocket formed in said first-named casing, said first-named casing having oppositely-disposed 55 key-openings, a lug carried by said lock-casing engaging one of the key-openings in the first-named casing, said lock-casing having a key-opening in registration with the other of said first-named key-openings, and 60 locking mechanism mounted in said lock-

casing for holding the latching-bolt in operative latching position.

4. A latch comprising a casing, a rigid pendulous bar mounted therein, a latch bolt connected with the lower end portion thereof, and a stop mounted in said casing in position to engage the inner edge of said bar when it is swung back far enough to carry the latch bolt out of operative position, whereby said bolt may be caused to rebound to its operative position.

5. A latch comprising a casing, a rigid pendulous bar mounted therein, a latch bolt connected with the lower end portion thereof, and a set screw adjustably mounted in 75 said casing in position to engage the inner edge of said bar when it is swung back far enough to carry the latch-bolt out of operative position, whereby said bolt may be caused to rebound to its operative position.

6. A latch comprising a casing, a pendulous bar mounted therein, a latch bolt connected with the lower end portion thereof, and a locking bolt mounted in said casing in diagonal relation to said latch bolt 85 and movable into or out of operative engagement therewith.

7. A latch comprising a casing, a pendulous bar mounted therein, a latch bolt connected with the lower end portion thereof, the inner end of said latch bolt being beveled, and a locking bolt mounted in said casing in diagonal relation to said latch bolt and movable into engagement with the beveled end thereof when said latch bolt is 90 in operative position.

8. A latch comprising a casing, a pendulous bar mounted therein, a latch-bolt connected with the lower end portion thereof, a locking bolt arranged diagonally with 100 reference to said latch-bolt when the latter is in its operative position, and being movable into or out of engagement with said latch bolt, and a casing for said locking bolt mounted in the latch casing, said locking bolt casing being arranged so that a portion thereof lies above the plane of the lower margin of the latch bolt when the latter is 105 in operative position.

9. A latch comprising a casing, a pendulous bar mounted in said casing, a horizontally-disposed latching-bolt mounted on the lower end of said pendulous bar, means connected with said pendulous bar for operating said latching-bolt, and a set-screw in 110 said casing in the path of said pendulous bar for adjustably limiting the backward movement of the latching-bolt.
